UNITED STATES PATENT OFFICE

CHARLES P. HARRISON, OF WESLEYVILLE, PENNSYLVANIA, ASSIGNOR TO JARECKI MANUFACTURING CO., OF ERIE, PENNSYLVANIA, A CORPORATION OF PENNSYLVANIA

DIE HEAD

Application filed August 5, 1929. Serial No. 383,571.

This invention relates to a die head for threading pipe upon the type of machine in which several sizes of pipe are threaded in the same die head without changing chasers 5 for the different sizes of pipe.

It is an object of this invention to provide means whereby the die head will open automatically when the pipe has been threaded to any standard length. Devices with this 10 general object have heretofore been proposed but they were limited to a single standard and allowed at the most but very slight variations, either long or short, from such standard.

Another object of the invention is to provide means whereby an opening device can be made to operate at the correct thread length of different standards of threads or at a length measurable on a dial in inch graduations. Standards for threads on pipe have undergone a change. There was a time when the Briggs standard covered nearly all requirements, but now we have the American Petroleum Institute (A. P. I.) standards 20 which are being adopted in the oil fields, therefore, it is an object of this invention to also cover these new standards as well as the old.

Another object of the invention is to provide means whereby the tripping device is automatically withdrawn from the work by power as the die opens and returns when die is closed again. It has heretofore been proposed to provide tripping devices or triggers 30 for causing the die heads on such machines as screw threading machines to open automatically when the thread is finished, but in such machines the trigger had to be moved out of operative position by the threaded pipe 40 and experience shows that the finished thread was often marred by the trigger, which drags over the thread in being so withdrawn from operative position.

Another object of the invention is to provide means whereby the operating means is connected to the carriage instead of the die head, which makes a better and simpler application for a taper attachment.

Another object of the invention is to provide means whereby the setting means has a

revolving or worm action for setting to size, and a sliding or rack action for opening and closing.

Referring to the drawings which are hereby made a part hereof, and on which similar reference characters indicate similar parts:

Fig. 1 is a front elevation of the die head and operating device with the die in closed or threading position,

Fig. 2, a side elevation of said head viewed 60 from the right,

Fig. 3, an enlarged front view of the operating device, with parts in section,

Fig. 4, a side elevation of said device viewed 65 from the right,

Fig. 5 is a front elevation of the die head showing the operating device when the die is in open position, and

Fig. 6, a side elevation of said die head and device viewed from the right.

In the drawings reference character 7 indicates a die head mounted on a supporting bracket 8 which is secured to the sliding carriage 9, the same being slidably mounted on a bed 10.

A set of chasers 11 is shown in Fig. 1 as being mounted in a circular series about the work, the chasers being mounted in chaser holders 12 (Fig. 3), which chaser holders are mounted for radial adjustment in slots in the die head 7. The chaser holders are moved radially by means of a cam plate 13 mounted on the front of the die head in any suitable manner and arranged to be oscillated about the axis of the die head. The chaser holders or blocks are connected by means of known character to cam slots 14 in the cam plate. The cam plate can be adjusted about its axis to vary the position of the chaser holders according to the size of the work, an extreme position being indicated in the dotted lines in Fig. 1, this being for example an open position of the chaser holders and chasers for threading a pipe of small size. For adjusting the plate about its axis I have provided a

worm 15 on a shaft 16 said shaft having a hand wheel 17 for turning the shaft and the worm being splined to the shaft so as to be slidably endwise of the shaft and of its own length but being compelled to rotate with 95 100

- the shaft by means of the spline indicated at 18. The worm wheel engages teeth (indicated in Fig. 1) on the periphery of the cam plate and so rotates it to an extent indicated by the graduations at 19 in Figs. 2 and 6. It will be evident that such adjusting means for setting the chasers from one size to another is very efficient, permitting quick adjustment and also locking itself automatically in adjusted position.
- In addition to the adjusting movement of the cam plate by rotation of the worm I have also provided for opening and closing the head by moving the worm in the direction of its length so that it acts as a rack upon the rack teeth of the cam plate. For this purpose a coil spring 20 surrounds the shaft, this spring being shown in compressed position in Fig. 1 and in expanded position in Fig. 5.
- Adjusting means for varying the pressure of the spring against the end of the worm comprises an externally threaded sleeve 27 engaging threads in the adjacent part of casting 9. Rotation of the head 28 of this sleeve 25 adjusts the tension of the spring to the correct extent for opening the die head. The spring tends to move the worm to the right for opening the head. For moving the worm as a rack to the left a sleeve 29 encircles the shaft 16 said sleeve being held against rotation by a roller 30 secured by a screw 31 to the sleeve 29, said roller being free to move in a direction parallel to shaft 16 along a slot whose ends are indicated at 32, 32 in Fig. 1.
- The sleeve 29 has a cam face 33 and a flat end face at 34. A sleeve 35 coaxial with shaft 16 is provided at one end with a handle 36 and at the other with a cam face 37 adapted to cooperate with the cam face 33 for moving the sleeve 29 and the worm 15 to the left. At the end of such movement a flat end face 40 (Fig. 3) on sleeve 35 rides up on the end face of sleeve 29, as indicated in Fig. 1, so that the parts are securely held against the action of spring 20. The enlarged inner end of sleeve 35 has a shoulder at 41 bearing against the thrust washer 42 located between such shoulder and the adjacent portion of the sliding carriage 9.
- A spring pressed plunger 43 (Fig. 2) bears against a downwardly projecting lug 44 on the lever 36, this plunger serving to rotate the sleeve 35 far enough to carry the flat end faces 34 and 40 out of engagement with one another after which the spring 20 can move the worm 15 and the sleeve 29 to the right for the purpose of opening the die head by retracting the chaser holders in radial direction. A detent 45 (best shown in Fig. 4) holds the lever 36 against the action of the spring pressed plunger, the forward end of the detent engaging a shoulder 46 on the lever for this purpose. Screw 47 secures a hardened steel plate 45' to the detent 45 so that when the action of latching and unlatching

rounds the corner of plate 45', it can be turned over and a new corner presented to the shoulder 46 for increased wear.

Automatic means for opening the head at the completion of the work includes a trip or trigger 48 fixed to a shaft 49 carrying a pinion 50 meshing with rack teeth at 51 on the vertical shaft 52. A spring 53 encircles the shaft, said spring bearing at one end of a collar 54 fixed to the shaft and at the other end against a bracket 55, thereby holding the shaft normally in elevated position with the trigger in position to engage the work. At the lower end of the shaft a set screw 56 provides adjustable means for engagement with the detent 45. A spring 57 normally holds the detent in position to engage the shoulder 46 and hold the lever 36 in the position indicated in Fig. 2 until released by the pressure of the shaft 52.

Adjusting means for varying the length of the thread is provided in connection with the shaft 49 and pinion 50. Such means comprises a thrust washer 58 bearing against a shoulder on shaft 49 and a dial 59 having graduations in various series according to different standards, here illustrated as comprising the Briggs standard and the A. P. I. (American Petroleum Institute) standard. An arm 60 carries an index finger 61 extending over the face of the graduated dial 59. The dial is splined to the shaft and the arm 60 is loosely mounted on an extension of the body of the pinion 50. A nut 62 on the threaded end of shaft 49 provides means whereby the dial, the arm, the pinion and the thrust washer may be clamped together against the shoulder on shaft 49 after the indicator finger has been properly positioned on the face of the graduated dial, thus bringing the trigger 48 to desired position relative to the end of the pipe to be threaded.

In setting the trip the nut 62 is backed off to permit rotation of finger 60 and pinion 50. The shaft 49 is turned to bring the trip 48 to desired position, the finger is brought into vertical position and the nut 62 is again tightened to clamp finger 60 and pinion 50 to the shaft. The finger will now indicate on the scale a different position, corresponding to the new position of the trip, and this will be shown according to both the A. P. I. standard and the Briggs standard.

For moving the trigger out of the way of the work so that it will not drag over the threads on the same a vertical shaft 63 is mounted for reciprocation in the bracket 55, said shaft having at its lower end a projecting stud 64 for engagement with a lug 65 (Figs. 1 and 3) on lever 36. The shaft 63 is held in its uppermost position by a spring 66 bearing at one end on the bracket and at the other end on an arm 67 fixed to the shaft and also encircling shaft 52 above the collar 54.

In the operation of my device the die head is set according to the size of the work by rotating hand wheel 17 in one direction or the other to bring the chasers to proper position.

5 Thereupon the handle 36 is oscillated from the position of Fig. 6 to that of Fig. 2, the cam face 37 sliding over cam face 33 and forcing the sleeve 29 and worm 18 to the left to rotate the cam plate 13, thus bringing the 10 chasers into closed or working position as shown in dotted lines in Fig. 1. As the head reaches closed position the face 40 rides upon the face 34 and the detent 45 engages shoulder 46. The work of the head now proceeds until 15 the end of the thread is reached, whereupon the end of the work strikes trigger 48, swinging the same from the position of Fig. 2 toward the position of Fig. 6. The pinion 50 now moves the shaft 52 downward until 20 such movement releases detent 45 whereupon plunger 43 forces the projection 44 of lever 36 to the left in Fig. 2 until the face 40 is free of face 34 whereupon spring 20 moves the worm 18 and sleeve 29 to the right, the action 25 of the cam faces on the sleeves 29 and 35 throwing the lever 36 to its extreme position illustrated in Fig. 6. In its movement toward this position the lug 65 on the lever strikes stud 64 and pulls down shaft 63 with its 30 arm 67 whereupon arm 67 strikes collar 54 and forces shaft 52 to its extreme downward position, thereby throwing trigger 48 into the dotted line position of Fig. 6 out of the way of the work. After removal of the work and 35 entry of a new piece of work the movement of lever 36 back toward the position of Fig. 2 releases shafts 63 and 52 thus permitting the springs 66 and 53 to elevate the shafts back to their working position and bring trigger 48 40 into working position.

It will be obvious to those skilled in the art that many changes may be made in the construction above described and therefore I do not limit myself to the details shown in the 45 drawings and described in the specification but only as indicated in the appended claims.

Having thus fully described my said invention, what I claim as new and desire to secure by Letters Patent is:—

50 1. A die head comprising a set of radially movable chasers, a cam plate connected to all the chasers, a worm engaging teeth on the cam plate for adjusting the setting of the chasers, means for rotating the worm, and 55 means for giving the worm an endwise movement for opening and closing the head, said last-named means including a trip in the path of the work, substantially as set forth.

2. A die head comprising a set of radially 60 movable chasers, a cam plate connected to all the chasers, a worm engaging teeth on the cam plate for adjusting the setting of the chasers, means for rotating the worm, means for giving the worm an endwise movement 65 for opening and closing the head, said last-

named means including a trip in the path of the work, and automatic means acting to move the trip out of the way of the work in connection with the operation of opening the head, substantially as set forth. 70

3. In a device of the character described, a bed, a carriage slidable thereon, a die head on the carriage, chasers on the head, a cam plate connected to the chasers, said cam plate having gear teeth a worm on the carriage engaging said teeth, means for rotating the worm to set the chasers for different sizes of the work, automatic means on the carriage for moving the worm endwise to cause it to act as a rack for opening the head, a trip on the head in the path of the work, means to prevent operation of said automatic means while the die head is in operation, and connections from said trip to release the last-named means, substantially as set forth. 75

4. A machine of the character described, comprising a die head, and chasers thereon, in combination with automatic means for opening the head including a gauge in the path of the work, a shaft connected to the gauge to be oscillated by movement thereof, a dial secured to the shaft to oscillate therewith, a pinion encircling the shaft and adjustable about the same, an indicating finger for the dial releasably secured to said pinion, means for securing the finger and pinion in adjusted position on the shaft, a spring-pressed plunger having rack teeth engaging the pinion, a handle for closing the head, and a detent for said handle, said detent being in position to be tripped by said plunger, substantially as set forth. 80

5. In a machine of the character described, a bed, a carriage thereon, a die head on the carriage, chasers on the head, a cam plate connected to the chasers, a worm engaging with teeth on the cam plate, a shaft on the carriage independent of the head to which shaft the worm is splined, means for rotating the shaft to adjust the chasers, resilient means for moving the worm toward one end of the shaft, and a handle on the carriage apart from the head, said handle being connected to the worm for moving it toward the other end of the shaft the endwise movement of the worm serving to open and close the head, substantially as set forth. 85

6. In a machine of the character described, a bed, a carriage thereon, a die head on the carriage, chasers on the head, a cam plate connected to the chasers, a worm engaging with teeth on the cam plate, a shaft on the carriage apart from the head to which shaft the worm is splined, means for rotating the shaft and the worm to adjust the chasers, resilient means for moving the worm endwise along the shaft in one direction, a sleeve encircling the shaft adjacent the worm and having a cam face, means for holding said sleeve against rotation, and a sleeve having 120

130

a handle and also having means coacting with the said cam face for moving the first-named sleeve and the worm along the shaft in the opposite direction whereby the endwise movements of the worm rotate the cam plate to open and close the head, substantially as set forth.

7. A device as in claim 6 combined with means encircling the shaft for adjusting the tension of the spring.

8. A machine of the character described, comprising a die head and chasers thereon, in combination with automatic means for opening the head including a trip in the path of the work, a handle on the carriage independent of the head, said handle being connected to open and close the head, means to hold the handle in head-closing position, means biased to release the holding means, and connection from said trip to the releasing means including a dial having concentric scales of different standards thereon, and an indicating finger adjustable to different positions on the dial for indicating the time of opening of the head, substantially as set forth.

9. A pipe threading machine having a die head, chasers thereon, means to stop the threading action on completion of a predetermined length of thread said means including a trigger in the path of the work, adjusting means for varying the length of the thread according to different standards said adjusting means including an element having a face visible from the working of the operator and having on said face a plurality of scales of different character, connections from said element to the trigger, an index finger cooperating with said scales, and connections from said finger to the stopping means.

10. A die head comprising a set of chasers, a cam plate connected to the chasers for moving them toward or from the work, means for actuating the cam plate including a worm engaging teeth on the cam plate, a shaft for turning the worm, a sleeve on the shaft, and coacting cam faces on the sleeve and the worm whereby a partial rotation of the sleeve moves the worm endwise to a sufficient extent for fully opening the head.

11. A die head comprising a set of chasers, a cam plate connected to the chasers for moving them toward or from the work, means for actuating the cam plate including a rotary shaft, a worm splined to the shaft, teeth on the cam plate engaging the worm, a sleeve on the shaft, means whereby the sleeve may be rotated independently of the shaft, and connections from the sleeve to the worm whereby a partial rotation of the sleeve moves the worm along the shaft to carry the chasers to their outermost position.

In testimony whereof I affix my signature.
CHARLES P. HARRISON.
